(57) **CLAIM**

I claim the ornamental design for a combined battery and component for battery, as shown and described.

DESCRIPTION

FIG. 1 is an upper perspective view of a battery, component for battery, and accessory for battery, showing my new design;

FIG. 2 is a lower perspective view of the design of FIG. 1;
FIG. 3 is a front elevation view of the design of FIG. 1;
FIG. 4 is a rear elevation view of the design of FIG. 1;
FIG. 5 is a right side elevation view of the design of FIG. 1;
FIG. 6 is a left side elevation view of the design of FIG. 1;
FIG. 7 is a top plan view of the design of FIG. 1; and,
FIG. 8 is a top plan view of the design of FIG. 1.
